MERCURY ACTUATED G-TRIGGERED
TIME DELAYSverre Kongelbeck, Silver Spring, Md., assignor to the
United States of America as represented by the Secretary
of the NavyFiled Apr. 10, 1961, Ser. No. 102,076
11 Claims. (Cl. 73—503)

This invention relates generally to a time delay mechanism; more particularly it relates to a mercury actuated acceleration responsive mechanism for use in actuating a desired element at a specified instant in time following the occurrence of an initial event.

It is the object of the present invention to provide a time delay mechanism so constructed as to be operable in response to acceleration, whereby to actuate a desired element at a specified instant in time following the termination of said acceleration.

A further object of this invention is to provide a timing unit for a time delay mechanism, said unit being so constructed as to integrate the product of acceleration and time to determine at what point after the initiation of said acceleration a specified velocity is attained, and to subsequently measure the passage of a specified time interval.

Another object of the present invention is to provide a timing unit for a time delay mechanism, said unit being so constructed as to permit a variety of periods of time delay.

It is also an object of the present invention to provide a time delay mechanism having means to actuate a source of stored energy.

A still further object of this invention is to provide an acceleration responsive time delay mechanism having means to prevent accidental operation thereof.

Another object of this invention is to provide a time delay mechanism so constructed that its operation will be entirely independent of ambient air conditions.

Other objects and many of the attendant advantages of this invention will be readily appreciated as the same becomes better understood by reference to the following detailed description when considered in connection with the accompanying drawings, wherein:

FIG. 1 is a perspective view of the time delay mechanism of the invention;

FIG. 2 is an enlarged longitudinal section of the mechanism, showing the construction thereof;

FIG. 3 is an axial section, on the line 3—3 of FIG. 2, the mechanism being shown in full lines at an intermediate position during the first, or acceleration integrating, half of the operating cycle, the initial position of the cam and link being indicated in broken lines;

FIG. 4 is a detail side elevation further showing the movement of elements of the mechanism during the operating cycle, the positions of the cam, the link and the plunger, after completion of the first, or acceleration integrating, half of the cycle being indicated in full lines, and the final positions of said three elements after completion of the second, or time delay, half of the cycle, being shown in broken lines;

FIG. 5 is a detail sectional view showing the actuating unit portion of the mechanism after the plungers have been released from their cocked positions; and

FIG. 6 is a detail section of a modified form of the cylindrical core of the mechanism.

The present invention relates to a mercury actuated acceleration responsive time delay mechanism. Time delay mechanisms are employed in applications where one element must be actuated at a predetermined instant in time following the occurrence of some initial event.

2

For example, they may be employed to actuate the ejection mechanism of an aerial missile nose cone at a predetermined instant in time following the termination of thrust generated by the missile's engine. The time delay mechanism which is the subject of the instant invention is operated by acceleration-created G-forces and is therefore capable of use in any application where accelerations of a sufficient magnitude are present, such as in rocket propelled missiles. Moreover, since the time delay mechanism of the instant invention employs a self-contained actuating fluid it is completely independent of ambient air pressure.

As is shown in FIGS. 2 and 3, the device consists of three principal components, a mercury actuated timing unit A, and actuating B, and a linkage system C operably connecting the timing unit A with the actuating unit B.

The mercury actuated timing unit A includes a cylindrical housing 2 having screw threads 4 and 6 on its inner surface at the upper and lower ends thereof, respectively. An integral, inwardly directed annular projection 8 is positioned centrally within said housing 2, the upper end face of said projection forming an abutment wall 10. Disposed within the housing 2 is a core assembly 12.

The core assembly 12 includes a central core 14 having an integral annular flange 16 positioned medially thereof, said flange having upper and lower radial end faces 18 and 20, each of which has an annular groove 22 and 24, respectively, therein. The flange 16 also has a plurality of circumferentially-spaced bores 26 there-through, said bores being positioned radially outwardly of the annular grooves 22 and 24.

Secured to the upper and lower end faces 18 and 20 of flange 16 by a pair of retainer rings 28 and 30 and a plurality of screws 32 are an upper bellows 34 and a lower bellows 36, the bellows each being constructed of a flexible, resilient, chemically-inert material such as polyethylene. The bellows are closed at their outer ends and have radially-projecting rims at their inner ends, which rims are clamped to the end faces 18 and 20 of annular flange 16 by the retainer rings 28 and 30, said retainer rings having rounded annular projections 38 and 40, respectively, thereon which cooperate with annular grooves 22 and 24 to secure the bellows to the end faces 18 and 20 in sealed relationship therewith. Each retainer ring 28 and 30 has a plurality of circumferentially-spaced bores 42 and 44, respectively, therein, one such bore being in alignment with each of the bores 26. The bores 44 are threaded, and the screws 32 are passed through the bores 42 and 26 and are threaded into the bores 44 to thereby secure the retainer rings and the bellows in position.

The core assembly 12 is disposed within housing 2 with the lower face of retainer ring 30 in engagement with abutment wall 10. A cylindrical cap member 46 having threads on the external lower end thereof is threaded into the upper end 4 of the housing 2, the lower end face 48 of said cap member being brought into abutment with the upper face of retainer ring 28 whereby the assembly 12 is clamped in position between said lower end face 48 and wall 10. The upper end face of the cap 46 has an annular socket 50 therewithin, there being a peripheral groove 52 in the axially-directed wall of said socket medially thereof. A cap plate 54 having a plurality of perforations 56 therein is disposed within the socket 50 and is secured in position by a snap ring 58, which ring is received within the groove 52.

The core 14 has a passageway extending longitudinally therethrough, said passageway being composed of an upper bore 60 of reduced diameter, a lower bore 62 of enlarged diameter, and a frustoconical seat portion 64 extending between said upper and lower bores 60 and

62, the upper end of the upper bore and the lower end of the lower bore having threads for securing therein a metering plug 66 and a retainer plate 68, respectively. The metering plug 66 has a bore 70 extending therethrough, and the retainer plate 68 has an orifice 72 disposed centrally thereof.

Disposed within the lower bore 62 is a piston 74 having a threaded bore 76 extending therethrough, the piston being substantially smaller in diameter than said bore 62. The external upper end portion of the piston is reduced in diameter, and has a peripheral groove 78 extending therearound for reception of an inturned radial flange portion 80 of a bushing 82. The bushing 82 is of a chemically inert resilient material such as Teflon, and serves to insure that a sealed relationship exists between the upper end of the piston 74 and the frusto-conical seat 64 when the former is in contact with the latter. The bushing 82 has a central opening therein of a diameter substantially the same as that of bore 76, and an orifice screw 84 extends through said opening and is threaded into said bore 76, the orifice screw having a central bore 86 extending therethrough. The upper end of the screw 84 is circumferentially enlarged, the enlarged portion serving to clamp the bushing in position. The bottom face of piston 74 and the top face of plate 68 have recesses 88 and 90 therein, respectively, and a coil spring 92 is positioned to extend between the bottom radial walls of said recesses, said spring 92 serving to urge the piston upwardly to cause the bushing-bearing upper end thereof to engage seat 64.

The core 14 has a pair of generally radially directed bores 94 and 96 therein, which bores place the bore 62 in communication with the space between lower bellows 36 and the exterior cylindrical surface of said core. The annular flange 16 has an elbow-shaped bore 98 therein, the radially-outward end of said bore being threaded for reception of a screw plug 100. The screw plug 100 carries an O-ring 102 thereon, which is received within an annular socket portion 104 of the bore 98 to thereby seal the plug relative to the annular flange. The axially-directed portion of bore 98 confronts the space between the lower bellows 36 and the cylindrical exterior of the core 14.

Disposed within the housing 2 below the lower bellows 36 is a bearing plate 106 having a diameter smaller than the diameter of said housing. The top face of the bearing plate has a recess 108 therein of a size to easily receive the closed outer end of the lower bellows. An end closure plate 110 is screwed into the threaded lower end 6 of the housing 2, said plate having a deep recess 112 in the top face thereof and a large central opening 114. A coil spring 116 extends between the lower face of the bearing plate 106 and the bottom wall of the recess 112 in plate 110, said lower face and said bottom wall having therein annular grooves 118 and 120, respectively, for receiving the opposite ends of the spring 116. The spring 116 functions to normally urge the bearing plate 106 upwardly, whereby to compress the lower bellows 36.

The initial position for the core assembly 12 is that shown in FIG. 2, with the lower bellows 36 being held in a compressed position by the coil spring 116. While the assembly is in said initial position the interior thereof is filled with mercury 122, the mercury occupying the volume defined by the expanded upper bellows, the compressed lower bellows, core 14, piston 74, retainer plate 68, spring 92, plug 66 and screw 84. The mercury is admitted to the interior of the assembly 12 through elbow-shaped bore 98, and thence flows through bores 92, 94, 96, 70, and 86 and orifice 72 until the interior of said assembly is fully occupied thereby. Screw plug 100 is then inserted, thus sealing the mercury within the core assembly.

The timing unit A is constructed so as to function as an acceleration integrator during the first half of its operating cycle and as a timer during the last half of said

cycle. With the mercury 122 contained within the upper bellows the timing unit is accelerated in an upward direction. Such acceleration creates G-forces which cause the mercury to depress bearing plate 106 against the force of spring 116, whereupon the mercury flows into the lower bellows, the precise course followed thereby being more fully described hereinafter. The amount of mercury transferred from the upper bellows to the lower bellows is proportional to the degree of acceleration and 10 the time over which it is exerted; hence the timing unit 15 actually integrates the product of acceleration and time over the period during which acceleration is occurring. The spring 116 acts as a bias on the integrating action, since the force exerted thereby must first be overcome 20 before the lower bellows can expand to permit commencement of the flow of mercury thereinto. Thus, if the bias is substantially greater than one G small accelerations exerted over short periods of time may not be sufficient to overcome the force of spring 116, and no 25 flow of mercury will occur.

When acceleration-created forces decline and the flow of mercury into the lower bellows ceases the piston 74 is urged into contact with seat 64. The second, or time delay, half of the timing devices operating cycle then 25 commences. The spring 116 urges the lower bellows upward, thus causing the mercury to flow through bores 86 and 70 back into the upper bellows at a rate determined primarily by the force exerted by said spring 116 and by the size of said bores. In the mechanism of the 30 invention the expanding and collapsing movements of the lower bellows during the acceleration integrating and timing halves, respectively, of the timing device's operating cycle are utilized to operate a mechanical linkage system, which system in turn actuates a source of stored 35 energy.

The actuating unit B includes an elongated, generally rectangular housing 124 having therein a centrally positioned bore 126 and first and second elongated chambers 128 and 130, the bore 126 and the chambers 128 and 40 130 lying in a common plane and being parallel to one another and to the longitudinal axis of said housing. Four integral, spaced posts 132 of equal length extend upwardly from the housing 124 into abutment with closure plate 110, said posts each being connected to said 45 closure plate by a screw 134 which passes through said closure plate and into a threaded bore in the upper end face of the post.

An annular lip 136 is formed about the upper end of the bore 126, and the shank portion 138 of a plunger 140 extends through the opening defined by said lip and into 50 the bore 126. The plunger 140 has an integral annular collar 142 positioned near the lower end thereof, and a spring 144 is disposed about the shank 138 and extends between the lip 136 and the upper face of said collar 142 for urging the plunger into the bore 126. The lower 55 end of the plunger is enlarged to form a cylindrical head portion 146, there being a circumferential groove 148 defined between the head 146 and the collar 142, the lower side wall 150 of said groove being tapered.

Positioned within each of the chambers 128 and 130 60 is an impact piston 152. Each of the pistons 152 includes an enlarged head portion 154 and a reduced in diameter shank portion 156, a radial shoulder 158 extending between the outer cylindrical surface of the head portion and the shank. The lower ends of the head portions 154 are reduced in diameter to form rounded annular shoulders 160. A coil spring 162 is disposed about each shank 156 and extends between shoulder 158 and the bottom wall of the chamber within which the piston is 65 disposed, said spring serving to urge the piston downwardly within said chamber.

Openings 164 and 166 are provided in the adjoining 70 walls between central bore 126 and the first and second chambers 128 and 130, said openings being positioned to 75 confront the shoulders 160 when the pistons 152 are in

their cocked positions as shown in FIG. 2, the springs 162 being compressed and the upper end faces of the shanks 156 being in engagement with the bottom walls of their respective chambers. Retaining balls 168 are disposed within the openings 164 and 166 and cooperate with the shoulders 160 and the cylindrical outer surface of the head portion 146 of plunger 140 to maintain the pistons 152 in said cocked positions. Upon downward movement of the plunger 140 within its bore 126 the groove 148 will be brought into alignment with the balls 168, said balls thereupon being urged into said groove by the combined action of the springs 162 and rounded shoulder 160. When the balls have moved a sufficient distance into the groove 148 the impact pistons 152 are free to move. The impact pistons each strike one of a pair of firing pins 170, said firing pins in turn actuating the desired device. The time delay unit of the instant invention can be employed to actuate any of a number of desired devices. In the embodiment shown in the drawings the firing pins 170 are utilized to puncture bottles 172 containing a compressed gas.

Referring to FIG. 2, a manifold 174 is attached to housing 124 by screws 176, a gasket 178 of suitable material being interposed therebetween. The manifold has a pair of reduced diameter bores 180 positioned to confront the first and second chambers 128 and 130 in housing 124, the firing pins 170 being slidably received within said bores. An O-ring 182 is positioned in an annular socket 184 at the upper end of each bore 180 and serves to maintain the firing pins in sealed relationship with the manifold. An enlarged bore 186 extends from each bore 180 and terminates in a flared outer end 188. A shoulder 190 is formed where the bores 180 and 186 meet, against which shoulder a collar 192 on the firing pin 170 abuts to thereby prevent the pin from extending too far into its chamber 128 or 130.

The bores 186 are placed in communication by a bore 194. Referring to FIG. 3, a transverse bore 196 intersects said bore 194 and contains an exhaust plug 198. The plug 198 has a collar 200 near one end thereof which cooperates with a nut 202 at its opposite end to secure the plug within said transverse bore 194, O-ring seals 204 and 206, positioned in annular recesses in the manifold 174 and the plug 198, respectively, being utilized to maintain the plug in sealed relationship. An annular recess 208 is positioned midway of the plug 198, and is in communication with bore 194. The plug contains an elbow-shaped outlet bore 210 which communicates with annular recess 208, bore 194, and the bores 186, whereby gas released from the bottles 172 may flow to the atmosphere.

The bottles 172 are each secured to confront one of the flared outer ends 188 by a bolt 212, a plate 214 and a nut 216 (FIG. 1), O-ring seals 218 being positioned in circumferential grooves in the bores 186 to place the outer ends of the bottles in sealed relationship with said bores.

The linkage system C, which is best seen in FIGS. 2 and 3, is contained partly within housing 2 and partly within housing 124, and includes a cam 220 pivotally connected by a shaft 222 to a pair of upstanding integral projections 224 and 226 on the housing 124. The projections 224 and 226 have aligned openings 228 and 230, respectively, therein, within which are disposed suitable flanged bushings 232 and 234. The shaft 222 passes through the bushings 232 and 234, and is secured in position by a pair of snap rings 236 positioned in peripheral grooves near the opposite ends thereof.

The cam 220 has an inner 238 and an outer 240 cam track therein, said cam tracks being in the shape of an arc and being drawn on radii emanating from a common point positioned at the center of the shaft 222. The inner and outer cam tracks are of a width to easily receive a cross-pin 242 carried by the plunger 140, and are connected at one end by a slot 244 which lies along a radius emanating from the center of shaft 222. The end of the

outer cam track 240 opposite the radial slot 244 is open, whereby to permit the cross-pin 242 to be inserted into said track. The upper end of the plunger 140 has a slot 246 therein, the cross-pin 242 being connected to the plunger near the upper end thereof and being adapted to extend across said slot.

The lower, forked end of a connecting link 248 is connected to a point 250 on the cam 220 by a pin 252, suitable bushings 254 and 256 being disposed between the 10 forked legs of the link and the opposite sides of the cam. The point 250 is positioned on a line which is substantially 90 degrees removed from a line emanating from the shaft 222 and bisecting the cam tracks 238 and 240, said point 250 being spaced from the shaft 222 a substantial distance whereby to define a lever arm. The upper end of the link 248 is connected to a yoke 258 by a pin 260, suitable bushings 262 and 264 being provided between the opposite sides of said link and the legs of said yoke. The yoke 258 has a shank 266 thereon which passes 20 through the central bores of roller bearing units 268 and 270 mounted in a hub portion 272 of bearing plate 106, a snap ring 274 disposed in a peripheral groove near the upper end of the shank 266 holding the same in position. The bearing units 268 and 270 are secured to the plate 25 106 by retainer plates 276 and 278 and screws 280 and 282, respectively.

The operation of the mechanism is as follows. The device as shown in FIG. 2 is in an unarmed position, the mercury 122 being contained within the upper bellows 34, 30 the impact pistons 152 being secured in their cocked positions, and the cross-pin 242 being disposed in the inner cam track 238. (The initial, unarmed positions of the cam 220 and link 248 are indicated by phantom lines in FIG. 3.) Upon rapid acceleration of the device in an 35 upward direction the acceleration integrating half of the operating cycle commences, and the following occurs. The acceleration, if great enough and if of a sufficient duration, creates G-forces which act on the mercury 122, pressing it downwardly. This in turn depresses piston 40 74, thus opening a passage therearound through which the mercury may flow at a rapid rate, such mercury passing through the opening 72 in the plate 68 and thence into the lower bellows 36, such flow, together with the G-forces, acting to force the bearing plate 106 downwardly. Bore 94 and 96 in the core and bore 86 in screw 84 facilitate the flow of mercury into the lower bellows. Downward movement of the bearing plate, because of the design of the cam 220 and the link 248, will cause the cam to swing in a clock-wise direction, the 45 amount of such swinging movement obviously being determined by the amount of mercury transferred into the lower bellows. FIG. 3 depicts the action of the device as G-forces are applied, the piston 74 being shown in its depressed, open position and the cam 220 being shown by solid lines in a partially shifted position. If the acceleration created forces are great enough and are of 50 sufficiently long duration swinging of cam 220 will continue until the cross-pin 242 reaches the end of the inner cam track 238, this position corresponding to a minimum velocity attained by the mechanism. At this point the spring 144 will cause the plunger 140 with its attached cross-pin 242 to move downwardly a small amount whereby the cross-pin will enter the outer cam track 240 via radial slot 244, this position being shown by solid lines 55 in FIG. 4. The device is then armed. If acceleration forces are insufficient or are too short in duration (which is equivalent to saying that if a specified minimum velocity is not attained), the cross-pin 242 will remain in the inner track 238, the device will not become armed, and 60 the mercury will be caused to flow back into the upper bellows by the action of spring 116.

Once the device is armed, and as long as it is being accelerated at such a rate that the magnitude of the G-forces does not decrease, no further action will occur. As soon as the G-forces begin to drop in magnitude the second, or

time delay and firing half of the operating cycle commences.

Upon a sufficient lowering of G-forces the spring 92 will urge the piston 74 into sealing engagement with the conical seat 64, the upper and lower bellows now being in communication only through the bore 86 within the screw 84. The spring 116 now exerts a force on the lower bellows 36 though the bearing plate 106, such force urging the mercury to flow from the lower bellows through the opening 72 and bores 86, 60 and 70 back into the upper bellows, the rate of such flow being regulated primarily by the size of the bore 86 within the screw 84. As flow of the mercury progresses the bearing plate 106 is caused to move upwardly, such action, because of the design of the linkage system, causing swinging of the cam 220 in a counter-clockwise direction. When the cam has shifted to the point where the cross-pin 242 is freed from the outer cam track 240 (this position being indicated by phantom lines in FIG. 4) the plunger 140 is caused to move into the central bore 126, thus freeing the impact pistons 152 in the manner explained hereinabove. This position is shown in FIG. 5. The firing cycle of the device is now complete.

As is evident from the above description, the length of the time delay from the beginning to the end of the firing half of the operating cycle is determined primarily by the rate of flow of mercury between the lower and upper bellows. Therefore, the length of the time delay may be preset to any one of an innumerable amount of periods by varying the size of the opening around the piston 74 when it is in its retracted position, the sizes of the bores 94 and 96, the size of the bore 86 in the screw 84, the size of the opening 72 in the plate 68, the size of the opening 70 in the plug 66, the size of the bellows, the amount of mercury utilized, or any combination of the above stated variables.

The time delay mechanism of the invention is especially suitable for use in the rocket propelled aerial missiles where an element must be actuated at a specified time after the rocket engine ceases operation. In such an application the timing device first operates to integrate the product of acceleration and time during the period up to a specified minimum velocity. If the rocket engine should fail before this minimum velocity is attained the amount of mercury transferred to the lower bellows will be insufficient to cause the cross-pin 242 to enter the outer cam track 240, and hence the mechanism will not be armed and the firing half of the operating cycle will not commence. If the amount and duration of thrust is sufficient to arm the mechanism, the time delay and firing half of said operating cycle will begin at thrust termination, and after passage of the preset period of time delay the desired device will be actuated.

It should also be realized that the timing unit A can function as a velocity indicator, although such a use is not shown in the drawings. During the first half of its operating cycle the timing device integrates the product of acceleration and time, the resultant of which integration is in reality velocity. Thus, the amount of mercury moved into the lower bellows (and hence the degree of enlargement of said bellows and the amount of rotational shifting movement of cam 220) is directly proportional to the velocity of the mechanism. Therefore, by measuring the displacement of cam 220 velocity can easily be determined. The maximum velocity than can be measured is of course determined primarily by the size of the bellows, the amount of mercury employed, and the rate of flow of the mercury between the bellows.

The cylindrical head 146 of the plunger 140 is provided with an opening 284, and the housing 124 is provided with a pair of opposed elongated slots 286, whereby a suitable tool may be inserted into the opening 284 to retract the plunger in order to prepare the device for operation.

In order to prevent an undesirable buildup of air pres-

sure within the chambers 128 and 130 upon release of the pistons 152, vent openings 287 are provided in the housing 124 near the lower end of each said chamber.

It has been found that a rapidly repeating, or vibrating, impact action of large magnitude may cause mercury to flow in small increments from the upper bellows into the lower bellows, thus operating the device in a ratchet-like manner. Since such a ratchet-type action could conceivably cause arming of the device before such is desired, an anti-ratchet modification of the device has been devised, such being shown in FIG. 6.

As shown in FIG. 6, a modified cylindrical core 288 is provided with a transverse bore 290 which is in communication with a longitudinal bore 292. The longitudinal bore 292 has therein a frusto-conical seat 294, a first portion 296, and a second, reduced portion 298. Disposed within the longitudinal bore 292 is a valve assembly comprising a spring 300, a ball 302 of a size to seat in sealed relationship on the conical seat 294, and an operating stem 304, the stem 304 having an enlarged portion 306 disposed within the first portion 296 of the longitudinal bore 292. The outer end of bore 290 is sealed by a plug 308, and a screw plug 310 is threaded into bore 292 to secure spring 300 in position. The remainder of the core 288 is identical in construction and operation to the core 14, and includes a central bore 60', a piston 74', a spring 92', a retainer plate 68' and a metering screw 66'.

In operation, the core 288 is mounted in the device of FIG. 2 in the same manner as core 14, with the lower end of stem 304 in contact with the end wall of lower bellows 36. The operating stem 304 is initially urged inwardly against the force of the spring 300 by the outer end of the lower bellows and the bearing plate 106, such action holding the ball 302 out of contact with the frusto-conical seat 294. Thus, a passageway between the first and second bellows is established through bore 60', the transverse bore 290, and the first portion 296 and the second portion 298 of bore 202, said portions 296 and 298 being substantially larger in diameter than the portions of the operating stem 304 contained therein. Therefore, any incremental amount of mercury that is moved from the upper bellows to the lower bellows by ratchet action is free to flow back into the upper bellows not only through the regular flow path defined by the elements of the core, but also through the passageway of the anti-ratchet mechanism. If the passageway of the anti-ratchet mechanism is of sufficient size the ratchet effect of the device may be overcome, thus preventing accidental arming thereof.

When a large, sustained acceleration acts upon the device the mercury will flow into the lower bellows in a rapid, continuous manner, thus enlarging said lower bellows at a rapid rate. As the lower bellows enlarges, the stem 304 is free to move and the spring 300 urges the ball 302 into sealing engagement with the frusto-conical seat 294, thus closing the passageway through the anti-ratchet mechanism. The timing device thereafter operates in the same manner as previously explained.

Obviously, many modifications and variations of the present invention are possible in the light of the above teachings. It is therefore to be understood that within the scope of the appended claims the invention may be practiced otherwise than as specifically described.

What is claimed is:

1. A time delay mechanism including a housing means, a G-force operated timing device mounted within said housing means, said device including a central core having passageway means extending therethrough, an upper bellows, a lower bellows, each of said bellows being closed at its outer end and being attached at its inner end to said core, the interiors of said upper and lower bellows being placed in communication by said passageway means, a fluid within and substantially filling one of said bellows when it is in an expanded position, movable flow restricting means within said passageway for allowing said fluid to flow from one of said bellows to the other thereof

more easily in one direction than in the other, and resilient means within said housing for urging said lower bellows toward a collapsed position, actuating apparatus also mounted within said housing means, and means within said housing means for operably connecting said timing unit with said actuating apparatus, said last-mentioned means being adapted to release said apparatus from a cocked position after passage of a predetermined period of time, as measured by the flow of fluid between the bellows within said timing device.

2. A time delay mechanism as recited in claim 1, wherein said actuating apparatus includes at least one piston, resilient means for biasing said piston toward a released position, and means for restraining said piston in a cocked position against the biasing force of said resilient means.

3. A time delay mechanism including a first housing, a G-force operated mercury controlled timing device mounted within said first housing, a second housing, said second housing being connected to said first housing and including a central bore at least one elongated chamber disposed parallel to said bore and a transverse opening extending between said central bore and said chamber, actuating apparatus contained within said second housing, said apparatus including a spring biased actuating piston disposed within said chamber, a spring biased plunger disposed within said central bore, a ball detent disposed within said opening and cooperable with portions of said plunger and said actuating piston to retain said actuating piston in a cocked position against the force of its biasing means, and connecting means disposed within said first and said second housings for operably connecting said timing device with said plunger, whereby said actuating piston will be released for movement after the passage of a predetermined period of time, as measured by said timing device.

4. A time delay mechanism including a first housing, a G-force operated timing device mounted within said first housing, said device including a central core having passageway means extending therethrough, an upper bellows, a lower bellows, each of said bellows being closed at its outer end and being attached in sealed relationship at its inner end to said core, the interiors of said upper and lower bellows being placed in communication by said passageway means, liquid mercury within and substantially filling one of said bellows when the bellows is in an expanded position, movable flow restricting means within said passageway for allowing said mercury to flow from one of said bellows to the other thereof more easily in one direction than in the other, and resilient means within said first housing for urging said lower bellows toward a collapsed position, a second housing, said second housing being connected to said first housing, actuating apparatus mounted within said second housing, said apparatus including at least one actuating piston, a resilient means for biasing said piston toward a released position, and means for restraining said actuating piston in a cocked position against the biasing force of said resilient means, and connecting means disposed within said first and second housings for operably connecting said timing unit with said restraining means, said connecting means being adapted to release said actuating piston from said cocked position after passage of a predetermined period of time, as measured by the flow of mercury between the bellows within the timing device.

5. A time delay mechanism as recited in claim 4, wherein said passageway means includes an upper bore portion, a lower bore portion of greater diameter than said upper bore portion, and an intermediate bore portion extending between said upper and said lower bore portions, the wall defining said intermediate bore portion forming an abutment surface, and wherein said flow restraining means includes a hollow piston, said piston being disposed within and being substantially smaller in diameter than said lower bore portion, and resilient means for

urging said hollow piston into sealing contact with said abutment surface.

6. A time delay mechanism as recited in claim 4, wherein said connecting means includes a cam element 5 pivotally connected to said second housing, means extending between and cooperable with said cam element and said lower bellows for causing said element to pivot to response to enlarging and collapsing movements of said lower bellows, and means releasably connecting said

10 restraining means with said cam element, whereby consecutive enlargement and collapsing movements of said lower bellows will cause said cam element to pivot sufficiently to release said last-mentioned connecting means.

7. A time delay mechanism as recited in claim 4, 15 wherein said core contains a second passageway means, said second passageway means placing the first-mentioned passageway means in communication with the lower bellows, and including means within said second passageway for closing the same when said lower bellows is in an 20 enlarged condition.

8. A time delay mechanism including a first housing, a G-force operated timing device mounted within said first housing, said device including a central core having passageway means extending therethrough, an upper bellows,

25 a lower bellows, each of said bellows being closed at its outer end and being attached in sealed relationship at its inner end to said core, the interiors of said upper and lower bellows being placed in communication by said passageway means, liquid mercury within and substantially

30 filling one of said bellows when it is in an expanded position, flow restricting means including a spring biased hollow piston disposed within said passageway for allowing said mercury to flow from the upper bellows to the lower bellows more easily than in the reverse direction,

35 and resilient means within said first housing for urging said lower bellows toward a collapsed position, a second housing, said second housing being connected to said first housing and including a central bore, at least one elongated chamber and an opening extending between said

40 central bore and said chamber, actuating apparatus contained within said second housing, said apparatus including an actuating piston disposed within said chamber, resilient means also disposed within said chamber for biasing said actuating piston toward a released position, a plunger disposed within said central bore, resilient means for urging said plunger into said central bore, a ball detent disposed within said opening and cooperable with portions of said plunger and said actuating piston to retain said actuating piston in position when it and said

45 plunger are both restrained against the force of their respective resilient means, said plunger having a reduced diameter portion thereon into which said ball detent enters when said plunger is released and moves into said central bore, such movement of said ball detent releasing said actuating piston for movement, and connecting means disposed within said first and said second housings for operably connecting said timing unit with said plunger, said connecting means being adapted to restrain said plunger against the force of its associated resilient means and to

50 release it for movement into said central bore after passage of a predetermined period of time, as measured by the flow of mercury between the bellows within the timing device.

9. A time delay mechanism as recited in claim 8, 55 wherein said connecting means includes a cam element pivotally connected to said second housing, said element having an inner and an outer cam track in communication with each other, said outer cam track being open at one end, means extending between and cooperable with said cam element and said lower bellows for causing said cam

60 element to pivot in response to enlarging and collapsing movements of said lower bellows, and pin means carried by said plunger and initially receivable within said inner cam track, whereby enlargement of said lower bellows resulting from the flow of mercury thereinto will cause said

11

cam element to pivot, causing said pin means to enter said outer cam track, and whereby subsequent collapsing movement of said lower bellows will cause said cam element to pivot in the opposite direction, thereby disengaging said pin means from said outer cam track and releasing said plunger.

10. An acceleration responsive timing device, said device including a housing, a central core mounted within said housing and having passageway means extending therethrough, an upper bellows, a lower bellows, each of said bellows being closed at its outer end and being attached in sealed relationship at its inner end to said core, the interiors of said upper and lower bellows being placed in communication by said passageway means, liquid mercury within and substantially filling said upper bellows when that bellows is in an expanded position, means within said passageway for controlling the flow of said mercury from one bellows to the other, and resilient means within said housing for urging said lower bellows into a collapsed position, whereby when said device is accelerated in an upward direction mercury will be transferred from the upper bellows to the lower bellows, the amount transferred and the consequent expanding movement of the lower bellows being proportional to the product of acceleration and time integrated over at least a portion 25 of the time duration of the acceleration, and whereby

12

5 after said acceleration ceases said resilient means will act to collapse the lower bellows and to thereby cause mercury contained therewithin to flow therefrom back into the upper bellows, the rate of such return flow being controlled by said flow controlling means in said passageway.

10 11. An acceleration responsive timing device as recited in claim 10, wherein said passageway means includes an upper bore portion, a lower bore portion of greater diameter than said upper bore portion, and an intermediate bore portion extending between said upper and said lower bore portion, the wall defining said intermediate bore portion forming an abutment surface, and wherein said means for controlling flow includes a piston having a bore therethrough, said piston being disposed within and being substantially smaller in diameter than said lower bore portion, and resilient means for urging said piston into sealing contact with said abutment surface, said bore within in said piston serving to meter the flow of mercury from the lower bellows into the upper bellows.
